UNITED STATES PATENT OFFICE.

EUGEN HAGENBUCHER, OF ESSEN, GERMANY, ASSIGNOR TO FRIED. KRUPP AKTIEN-
GESELLSCHAFT, OF ESSEN-ON-THE-RUHR, GERMANY.

LAYING GEAR.

Application filed January 3, 1921. Serial No. 424,608.

(GRANTED UNDER THE PROVISIONS OF THE ACT OF MARCH 3, 1921, 41 STAT. L., 1313.)

To all whom it may concern:

Be it known that I, EUGEN HAGENBUCHER, residing at Essen, Germany, a citizen of the German Republic, have invented a certain new and useful Improvement in Laying Gears, of which the following is a specification.

This invention relates to laying gear, in particular for ordnance, in the case of which a hydraulic driving mechanism is provided for the part to be pointed; the starting member of the said driving mechanism appertaining to a driving gear adapted to effect a return of the said starting member into its inoperative position in the course of the laying motion carried out by the hydraulic driving mechanism. More particularly, it is the object of the present invention to provide a form of construction for laying gear of this kind which will warrant a particularly exact laying operation.

An embodiment of the subject matter of the present invention will be described by way of example with reference to the accompanying drawing in which—

Fig. 1 is a diagrammatical elevation of a hydraulic elevating mechanism for ordnance.

Fig. 2 is a larger scale in detail of Fig. 1.
Fig. 3 is a sectional view along line 3—3 of Fig. 2, looking from the left, and,

Fig. 4 is a sectional view along line 4—4 of Fig. 3, looking from above.

Referring to this drawing, the gun barrel A is guided in the customary manner in a cradle A¹ which is lodged to rotate within the carriage B by means of two horizontal trunnions a². For the purpose of elevating the gun barrel A, there is provided a hydraulic driving mechanism, comprising a cylinder B¹ secured to the carriage B and enclosing a piston W having a piston rod W¹ connected to an arm a³ of the cradle A¹ and two slide valves C and D serving, when in the position illustrated, to shut off the cylinder B¹ with respect to the delivery piping, not shown. The arrangement of the slide valves C and D is such that they will be opened when moved in the direction indicated by the arrows x and y, respectively, whereas when moved in the contrary sense out of the position illustrated, they keep shutting off the cylinder B¹ from the

delivery piping. The arrangement devised is such that when the slide valve C is opened the breech end of the gun barrel A will be lowered, whereas when the slide valve D is opened, it will be elevated. Each of the slide valves C and D is articulated by means of a rod E, F, respectively, pivoted thereto, with a bell-crank lever G or H respectively, having arms of different length and mounted to rotate on the carriage B. A spring J or K, respectively, tending to rotate said levers in the direction denoted by the arrows x, y, respectively, is secured to the end of the longer arm of the bell-crank levers G, H, respectively, while to the shorter arm thereof there is mounted a roller M, N, respectively, bearing up under the impulse exerted by the springs J, K, respectively, against a bevel surface p¹, p², respectively, of a rod P. The surfaces p¹ and p² are disposed so as to converge and are limited by a vertically disposed receding surface p³ of the rod P. This latter is adapted to be vertically displaced on the carriage B and is pivotally connected by means of an intermediate rod p⁴ to a toothed arc Q loosely mounted to rotate on the horizontal trunnion a² visible in the drawing. The toothed arc Q is positively connected to the armature shaft r¹ of an electromotor R mounted on the cradle A¹, said connection being effected in the manner illustrated, by intervention of a self-locking worm gear. In addition, there is arranged on the cradle A¹ in a casing a⁵ mounted thereon, the receiver motor T, (Figs. 3 and 4) of an electric long-distance control device. This receiver motor is adapted to be adjusted by a transmitter located at the commanding station to the particular elevation to be imparted to the gun barrel. In the casing a⁵ closed on the front side by a cover plate a⁶, there is arranged a rotatable shaft S, which carries a large spur wheel S¹ rigidly connected thereto and engaging a small spur wheel L which is rotatably mounted on the cradle A¹ out of the casing a⁵ and engages the toothed arc Q. The shaft U (Fig. 4) of the receiver motor T is coupled to a worm U¹ rotatable in the casing a⁵ and engaging a worm wheel V mounted on the shaft S to rotate relatively thereto. The hub of the worm wheel V carries a pointer v¹ rigidly

connected thereto which lies out of the casting a^3 over the front face of the cover plate a^4 and may register the elevation which is to be imparted to the gun barrel on a range scale a^5 arranged on the cover plate a^4 . The shaft S extends on its one end beyond the front face of the pointer v^1 and carries on this end a pointer s^2 having a mark s^3 (Fig. 2), which is in alignment with a mark v^2 10 of the pointer v^1 when the pointer s^2 has been adjusted by the electro-motor R and the train of gearing r^1 Q, L, S^1 S connected thereto to cover the pointer v^1 . The motor R , which may be started independently of 15 the long-distance control device, will be automatically brought to a stop in a well known manner as soon as the mark s^3 of the pointer s^2 is come into alignment with the mark v^2 of the pointer v^1 .

20 The manner of operation of the device is as follows:

When the breech end of the gun barrel A is to be lowered for an amount corresponding to the position assumed by the object 25 to be fired at, then the receiver motor T is adjusted from the transmitter, located at the commanding station, to the corresponding degree of elevation required which is indicated by the pointer v^1 on the scale a^5 . Upon 30 this, the electromotor R is started, and in such a direction that a rotation of the armature shaft r^1 will provoke a rotation of the toothed arc Q around the horizontal trunnion a^2 in the direction indicated by the arrow z and therewith a displacement in the 35 upward direction of the rod P . In the course of this displacement, the rollers M and N run along the bevelled surfaces p^1 and p^2 . The slide valve D being at the same time 40 moved in a direction counter to that indicated by the arrow y , this valve consequently remains closed, while the slide valve C is moved in the course of this operation in the sense denoted by the arrow x and consequently 45 is now opened; the full opening of this slide valve taking place the instant the roller M has passed from the bevel surface p^1 on to the vertical surface p^3 , which will happen in a very brief space of time. After 50 the slide valve C has been opened, the breech end of the gun barrel is lowered by the driving mechanism and the gun barrel consequently elevated. Now owing to the connection existing, as previously set forth, between 55 the gun barrel A and the rod P , the aforesaid movement affects the movement of the rod P ; and would result in the rod P being moved downward if the motor R were not running. The actual motion, however, 60 carried out by the rod P is due to the difference in the displacement the rod P is subjected to by the rotation of the armature shaft r^1 , on the one hand, and by the lowering of the breech end on the other. In this 65 connection, the speed conditions are prefer-

ably so chosen that the influence exerted by the motor will prevail, in other words, that the rod P will be raised as long as the motor R is running. As a result, the roller M remains in contact with the surface p^3 , so that the slide valve C while being now completely open will remain for the present in a state of rest. As soon as the motor R has rotated for an extent corresponding to the elevation to which the pointer v^1 has been adjusted, by the receiver motor T , the mark s^3 of the pointer s^2 is come into alignment with the mark v^2 of the pointer v^1 and in consequence thereof the motor R is automatically brought to a stop. From this instant onward, the rod P begins to move downward. In so doing, finally the roller M rolls back on to the bevel surface p^1 . Then the slide valve C is moved counter to the direction indicated by the arrow x by intervention of the bell-crank lever G , so that it comes to be closed the moment the roller M has again taken up the position disclosed in the drawing. At this moment the driving mechanism stops working and the gun barrel A has obtained the elevation desired seeing that the arm Q , to which the motor R has imparted an angular position, with regard to the gun barrel and corresponding to this elevation, will again assume its original position with respect to the carriage.

Again if, say for example, for the purpose of loading, the breech end of the gun barrel is to be raised, then the motor R is started in the counter direction to that previously explained. As a result, the rod P is moved downward and the slide valve D is opened, while now the slide valve C remains closed. The slide valve D opening, the breech end begins to move upward, in consequence of which the speed of the downward motion of the rod P comes to be lessened. On the breech end having almost attained the position desired, the motor R is brought to a standstill. However, as the breech end for the present continues its upward movement, the rod P is now also raised, and as soon as it has attained its original position in height, the slide valve D again shuts down and the gun barrel comes to a stop.

As will be readily understood from the foregoing description, the rod P forming the starting member of the hydraulic driving mechanism appertains to a driving gear (B, A, A^1 , Q, p^4 , P) which is adapted to bring about a return of said starting member into its initial, inoperative position during the laying motion imparted to the gun barrel by the driving mechanism. Moreover, by reason of the fact that, in contradistinction to the known devices, two movable parts (A, A^1 and Q) of the driving gear serving to provoke the return operation are adapted, in accordance with the present invention, to be adjusted relatively to each other and in cor-

60

respondence with the elevation required, there is attained a considerable simplification of the driving gear and therewith a corresponding reduction of the sources of errors, so that by means of the described device a particularly exact laying of the gun barrel is obtained.

Claims.

1. A hydraulic laying gear for ordnance comprising a gun carriage, a gun barrel mounted for rotation upon said carriage, a hydraulic driving mechanism for elevating the gun barrel having a starting member causing said hydraulic driving mechanism 15 to function after being moved from its inoperative position to an operative position, a gun part adapted to turn in unison with the gun barrel, a movable member adapted to turn about the same axis as said gun part 20 independently thereof, means for adjusting said movable member for range, and means positively connecting said starting member to said adjustable movable member for returning the starting member into its inoperative position when the gun barrel is elevated by said hydraulic driving mechanism.

2. A hydraulic laying gear for ordnance comprising a gun carriage, a gun barrel mounted for rotation upon trunnions supported by said carriage, a movable member loosely mounted upon one of said trunnions and adjustable relatively to said gun barrel, means mounted upon said carriage and connected to said movable member for controlling a hydraulic driving mechanism and means mounted to move with said gun barrel for adjusting said movable member with respect to said gun barrel corresponding to the 40 desired elevation to be given to the gun barrel.

3. A hydraulic laying gear for ordnance comprising a gun carriage, a gun barrel provided with trunnions and mounted for rotation within said carriage, a movable member supported by one of said trunnions and adjustable relatively to said gun barrel, means mounted upon said carriage for controlling a hydraulic driving mechanism, said 45 control means embodying a starting member, means connecting said starting member to said movable member mounted upon said trunnion, means mounted to move with said gun barrel and engaging said movable member for adjusting it with respect to said gun barrel corresponding to the desired elevation to be given to the gun barrel, whereby said starting member will be first moved to cause said control means to function, the

movement of said gun barrel as it assumes its position of elevation, returning said starting member to its inoperative position.

4. A laying gear for ordnance embodying a hydraulic driving mechanism comprising a gun carriage, a gun barrel provided with a pair of horizontal trunnions and rotatably supported within said carriage, an arm loosely mounted upon one of said trunnions and independent of said gun barrel, said arm being adjustable relatively to the gun barrel to positions corresponding to the elevation to be given to the latter, valve mechanism secured to the carriage for controlling a hydraulic lifting mechanism, said valve mechanism embodying a slideable starting rod, means connecting said movable arm to said slide rod whereby a movement of said arm causes a corresponding displacement of said slide rod, means movable with said gun barrel for adjusting said movable arm to a position corresponding to the elevation to be imparted to the gun barrel, the connection between said gun barrel and said slide rod being such that when said gun barrel reaches its position of elevation, said slide rod is returned to its inoperative position.

5. A laying gear for ordnance for use in combination with a hydraulic driving mechanism comprising a gun carriage, a gun barrel, horizontal trunnions rotatably supporting said gun barrel upon said carriage a member mounted upon one of said trunnions and adjustable relatively to said gun barrel, means mounted upon said carriage for controlling a hydraulic driving mechanism, means connecting said movable member to said hydraulic controlling means and means movable with said gun barrel for adjusting said movable member with respect to said gun barrel, to a position corresponding to the desired elevation to be given to said gun barrel whereby an adjustment of said movable member causes said controlling means to function, permitting said hydraulic driving mechanism to elevate the gun barrel, the connection between said gun barrel and the movable member being such that said control means is moved to its inoperative position as the gun barrel reaches the desired elevation.

The foregoing specification signed at Essen, Germany, this 29th day of October, 1920.
